UNITED STATES PATENT OFFICE.

FRANK. J. LYITTLE, OF HUMBOLDT, NEBRASKA.

CONVERTIBLE TRUNK AND WARDROBE.

SPECIFICATION forming part of Letters Patent No. 412,770, dated October 15, 1889.

Application filed May 2, 1889. Serial No. 309,373. (No model.)

To all whom it may concern:

Be it known that I, FRANK. J. LYITTLE, a citizen of the United States, residing at Humboldt, in the county of Richardson and State 5 of Nebraska, have invented a new and useful Convertible Trunk and Wardrobe, of which the following is a specification.

This invention relates to convertible trunks and wardrobes; and it has for its object to 10 construct a trunk which when not in use as such may be quickly and conveniently converted into a wardrobe, or vice versa.

The invention consists in the improved construction, arrangement, and combination of 15 parts, which will be hereinafter described, and particularly pointed out in the claims.

In the drawings, Figure 1 is a perspective view of a trunk embodying my improvements, showing the lid or cover of the same raised 20 and detached from the hinge. Fig. 2 is a longitudinal sectional view showing the trunk closed. Fig. 3 is a perspective view showing the trunk unfolded in the process of 25 converting it into a wardrobe. Fig. 4 is a perspective view showing the wardrobe complete. Fig. 5 is a detail view of the parts composing the front of the wardrobe. Fig. 6 is a detail horizontal sectional view taken on the line $\alpha\alpha$ in Fig. 4.

30 The same letters refer to the same parts in all the figures.

A designates the bottom of the trunk, to the edges of which the sides B B are connected, by means of hinges C C, in such a manner as 35 to fold outwardly from the same. The ends D D are likewise hinged to the bottom in such a manner as to fold down upon the latter, and to the ends of the sides B B are hinged end pieces E E, which may fold down upon 40 the said sides and fit between the end pieces of the trunk when the sides are raised to a vertical position, as when the trunk is in use. Metallic angle-plates or braces are secured to the bottom and to the sides of the trunk, as 45 shown in the drawings, and angular or L-shaped braces F F are likewise attached to the sides and to the ends D by means of screws G, which may be readily removed when it shall be desired to convert the same into 50 a wardrobe, as will be hereinafter more fully described.

It will be seen that when the trunk is in use the angle-irons F and screws G serve to connect the sides with the ends of the trunk, while the end pieces E E, hinged to the sides 55 B B, are folded upon the latter in such a manner that their hinged ends abut against the end pieces D, thereby preventing the said hinged pieces E E from being unfolded.

H designates a detachable bottom provided 60 along its edges with flanges I I, between which the bottom A of the trunk proper will fit, the said flanges I being of a width equal to the thickness of the sides B of the trunk, the lower edges of which will rest upon the 65 said flanges.

J designates the top or cover of the trunk, which is constructed in such a manner as to fit neatly upon the upper edge of the trunk-body. The hinges by means of which the 70 said cover is connected to the trunk are composed of the sections K, attached permanently to the upper edges of the rear side of the trunk and having the pintles L, and the sections M, attached to the rear edge of the 75 cover and having the hooks N, adapted to engage the pintles L in such a manner as to connect the cover detachably with the trunk-body.

In order to convert the trunk into a wardrobe, it is necessary, first, to remove the screws G, connecting the angle-irons F with the ends D of the trunk. The bottom H, which is secured detachably to the permanent bottom A of the trunk by means of 85 screws O, is then removed, and the sides B B may then be folded down in a line with the bottom A, after which the end pieces E E may be raised to a vertical position in a line with the end pieces D of the trunk. The 90 trunk-body is now raised or set on end, as shown in Fig. 3 of the drawings, and placed with the outer edge of the front section B and the adjacent hinged sections E E within the flange I of the bottom H. The front of 95 the wardrobe is next placed in position. Said front comprises a top strip P, provided on its rear side with cleats Q Q, adapted to fit between the inner sides of the hinged end pieces E E of the top section, which are 100 thereby spaced; a bottom strip R, which fits between the hinged end pieces of the bottom

section, and which is likewise provided with cleats Q Q to space the said end pieces; and vertical strips S S, adapted to be attached to the front edges of the hinged end pieces D D 5 and E E of the middle and top sections, and provided at their lower ends with dowel-pins T T, adapted to enter corresponding recesses U in the upper edge of the bottom strip R. To the inner edges of the strips S S are hinged 10 the doors V V, the upper edges of which are rabbeted to fit against the rabbeted lower edge of the top strip P. The strips P, R, and S may be attached to the front edges of the hinged pieces D E E by means of ordinary 15 wood-screws, or in any convenient manner, and when they and the cover or top J have been placed in position the wardrobe is complete and ready for use.

It will be observed that the parts which 20 form the front of the wardrobe do not constitute a portion of the trunk, but may, when the device is to be used as a trunk, be folded compactly together and stowed away. When the device is converted into a trunk, it will 25 be seen that only the end pieces E E fold within the latter, and they occupy but little space, while they serve materially to strengthen the sides and ends of the tongue, which for this reason is enabled to resist 30 rough usage.

My improved convertible trunk and wardrobe is exceedingly simple in construction, and is capable of being folded in such a manner as to occupy but little space while 35 being transported from the factory to the dealers, thereby effecting a great saving in expense for freight, which consumes a large portion of the profits on trunks of ordinary construction.

40 When the device is convertible into a wardrobe, it will be observed that a considerable space is left below the doors of the wardrobe, in which garments may be packed in the same manner as in an ordinary trunk, thereby greatly increasing the capacity and convenience of the wardrobe. It will be also noticed that the construction is such that the device may be converted from a trunk into a wardrobe, or vice versa, in a short time and 45 with slight difficulty.

Having thus described my invention, I claim—

1. In a convertible trunk, the combination, with the permanent bottom, of the hinged

sides and end pieces, the end pieces hinged 55 to the sides and folding inwardly upon the latter, and a false bottom having a flange extending around its sides and adapted to receive the permanent bottom, substantially as set forth.

2. In a convertible trunk, the combination of the bottom, the hinged side pieces, the end pieces hinged to the latter, the end pieces hinged to the bottom, the angle-plates secured to the sides, and screws for connecting 60 the said angle-plates detachably to the end pieces of the trunk-body, substantially as set forth.

3. In a convertible trunk, the combination, with the trunk-body having the hinged sides 70 and ends, and the end pieces hinged to the sides and folding inwardly upon the latter, of the detachable top or cover having hinge-plates provided with hooks adapted to engage the pintle of the hinge-plates attached to the 75 upper edge of the rear side of the trunk, substantially as set forth.

4. In a convertible trunk, the combination, with the trunk-body comprising the permanent bottom, the sides and ends hinged to the 80 latter, and the end pieces hinged to the sides and adapted to fold inwardly upon the latter, of the flanged bottom secured detachably to the under side of the permanent bottom, and the detachable top or cover, substantially as 85 and for the purpose set forth.

5. In a convertible trunk and wardrobe, the combination of the permanent trunk-bottom, the sides and ends hinged to the latter, the ends hinged to the side pieces and adapted to 90 fold inwardly upon the same, the angle-plates or braces secured to the sides and connected detachably with the ends of the trunk, the false bottom secured detachably to the under side of the permanent bottom, the top and 95 bottom strips provided on their rear sides with cleats, and the side strips having dowel-pins adapted to engage the recesses in the bottom strip and provided with hinged doors, substantially as herein described, and for the 100 purpose set forth.

In testimony that I claim the foregoing as my own I have hereto affixed my signature in presence of two witnesses.

FRANK. J. LYTLE.
